Patented Sept. 20, 1927.

1,642,900

UNITED STATES PATENT OFFICE.

DAVID FRANKLIN SMITH, OF WASHINGTON, DISTRICT OF COLUMBIA.

COMPRESSOR FOR REFRIGERATING MACHINERY.

Application filed October 1, 1923. Serial No. 666,375.

The object of the invention is to provide a compressor having a simple construction involving few parts, and in which the connections to the pistons will be free from bolts, nuts, screws or like fastening devices which are liable to become loose, drop out, and result in damage. Sometimes this damage consists in breaking the casing, and this allows the escape of the fumes which are dangerous to health and life.

In the drawings—

Fig. 1 is a vertical sectional view.

Fig. 2 is a part sectional view and side elevation of the machine a quarter turn from the position of Fig. 1.

The construction involves a one piece drive shaft A, having formed integral therewith an eccentric or eccentricities B. The straps C of these eccentricities are formed in one piece and roller bearings D are interposed between the eccentricities and their straps. The eccentric has a flange E formed integral therewith, and the eccentric strap has a flange C' formed integral therewith. The roller bearings D are inserted between the integral flanges of the eccentric and strap without use of any ports or gateways. For this purpose a thin shell or cage is used for holding the rollers, and this is with- drawn as the parts are placed together.

In the use of this shell it is placed within the eccentric strap and is of a diameter adapted to be thrust out or withdrawn from within the eccentric through the opening in the flange C'. After this shell is placed in position the roller bearings are placed around it and are thus properly located within the eccentric strap. The eccentric is then introduced into the eccentric strap and the shell is thrust out or withdrawn so that the eccentric takes its place during the withdrawal of the shell.

The eccentric bears against the frame at X, and thus it is held against lateral thrust. This is true also of the eccentric strap which bears against the frame at X'. There are two of these eccentricities with their straps, and the second pair bear against the frame at X', X'', so that these parts are sustained against lateral thrust and aid in keeping the parts in proper alignment for work. The shaft A works in end thrust bearings.

From the above construction it will be seen that there is no possibility of the rollers D falling out of place, or in practice, be-

coming disconnected because of the dropping out of fastening devices such as nuts, bolts, or screws. I have provided a construction which will be integral throughout the shaft and eccentricities and their flanges, and integral throughout the eccentric straps with their flanges, and I assemble these parts so that the rollers may be interposed without use of gateways which would necessitate closures, or other fastening devices.

It will be noticed that one of the flanges is on the eccentric and the other is on the strap. This simplifies the manufacture of these parts. The eccentric is made to come out flush with the side face of the eccentric strap so as to bear on the frame of the apparatus and sustain lateral thrust. The eccentric may be shouldered at X² for this purpose.

The chamber in which the eccentric and shaft are located is partly filled with lubricant which is thrown about to oil all of the contained parts.

The wrist pin is held in place by screws a which are inserted in a threaded socket formed partly in the wrist pin and partly in the piston. There is one of these screws at each end of the wrist pin and they are held in place against turning by keys b, consisting of flat metal pieces of T-shape seated in the central opening of the wrist pin and with their heads or cross arm portions seated in grooves or slots in the ends of the wrist pin and in kerfs in the screws. These locking keys are held in place by bearing on the wall of the cylinder. They are provided with notches c to form continuations of oil grooves in the cylinder.

The two cylinders are formed en bloc. The base of the cylinder casting is circular at d and a single gasket e surrounds the two cylinders, the seat for said gasket being circular. This construction is the same at the top of the structure, the cap and circular cap seat being common to both cylinders, and this construction aids manufacture and enables expeditious machine work to be done, i. e., on a lathe instead of a milling machine.

The induction port is at f and the education port at g. The one integral head or block carries both cylinders.

What is claimed is:—

In combination in a compressor a casing, a pair of cylinders and pistons, eccentricities integral with a shaft which bears in the

casing; a strap for each eccentric connected with the appropriate piston, anti-friction rollers between the eccentrics and eccentric straps, flanges of continuous form and integral with their carrying part and forming closures for the anti-friction rollers extending across the ends of the same, one of said eccentric and eccentric strap organizations having a bearing against the casing at one side of said organization to resist lateral

thrust, and the other eccentric and eccentric strap organization having a bearing against the casing at the side opposite to the bearing of the first organization, whereby the eccentrics with the integral shaft are held against lateral thrust, substantially as described. 16

In testimony whereof, I affix my signature.

DAVID FRANKLIN SMITH.
